UNITED STATES PATENT OFFICE

JOHN M. SCHILLING, OF LIMA, OHIO

BOTTLE COOLER

Application filed September 21, 1927. Serial No. 220,896.

My invention relates to an improved construction of cooler for bottled soft drinks by which filled bottles may be contained in carriers in a cooling tank and moved through the tank to have effectively exerted upon them the cooling action of the refrigerant in the tank, my construction further providing that there may be preferably a plurality of these carriers, one for each particular kind of soft drink to be cooled, and further that the removal of a cooled bottle from any one of the carriers must necessarily be followed by the insertion of another bottle to be cooled, before it is possible to remove a second cooled bottle from the same carrier, which result I accomplish without operating or controlling mechanism of any kind. A further object of my invention is to provide a carrier construction which is simple, novel and effective.

My invention will best be understood by reference to the accompanying drawings showing a preferred embodiment thereof in which—

25 Fig. 1 shows my cooler in plan view; Fig. 2 shows my cooler in front elevation;

Fig. 3 is a horizontal sectional view through the cooler taken along the line 3—3 in Figs. 2 and 4;

30 Fig. 4 is a sectional view of the parts shown in Fig. 3 taken along the line 4—4;

Fig. 5 is a side elevation to an enlarged scale of one of the carrier drums;

Fig. 6 is a sectional view of the parts 35 shown in Fig. 5 taken along the line 6—6, and

Fig. 7 is a sectional view of a part of the cover and parts adjacent thereto taken along the line 7—7 in Fig. 1.

40 Similar numerals refer to similar parts throughout the several views.

As shown in Figs. 1 and 2, my cooler consists of a cabinet 10 of wood or metal as preferred, having a removable cover 11 enclosing the entire top of the cabinet, and a rack 12 mounted in upright position over the rear portion of the cabinet and containing a plurality of vertical partitions 13 for maintaining bottles 14 in vertical rows, these 45 bottles containing the soft drinks to be

cooled and preferably arranged according to flavor or kind, one kind being conveniently kept in each vertical row, which rows may be designated if desired, by numerals as indicated in Fig. 2 on the edge of the top 55 member of the rack.

As indicated in Fig. 1 the cover 11 is provided with a plurality of service doors 15, 16, 17 and 18, so that one of these service doors is opened when it is desired to remove 60 a cooled bottle from the cooler, the particular one of the service doors which is opened depending on the flavor or kind of drink that is desired. The service doors are preferably hinged to the main cover 11 as indicated, but if desired, the hinges may be omitted. To facilitate the selection of the desired kind of drink, the service doors may be provided with numerals corresponding with the numerals on the rack 12, indicating 65 the kinds of drinks available through the service doors immediately below the numerals on them. The service doors 16 and 17 are separated a substantial distance, and between them, the cover 11 is provided with 70 a removable icing cover 19 which may be removed without interfering with the service doors or the main cover 11, to place ice in the cooler.

Within the cooler, a plurality of carrier 75 drums 20 is disposed on each side of an ice space, these drums being disposed in vertical planes and two of them being preferably disposed under each of the service doors referred to.

80 As indicated in Figs. 3 and 4, the cabinet 10 is provided with an inner lining forming a tank 21, preferably of metal and water tight to contain the refrigerant which preferably consists of water containing ice. Between the inner and outer walls of the cabinet, a filling of good heat insulating material is used as indicated at 22, for example ground cork. Each group of carrier drums 85 20 is mounted in a framework of skeleton 90 formation consisting of a first member 23 of rectangular conformation to rest against the front and rear walls of the tank 21, which member is disposed in a substantially horizontal plane, and a second member 24 which 95 100

is U-shaped and disposed in a vertical plane with its mid portion resting on the bottom of the tank 21. At least one leg of each member 24 is preferably extended upwardly beyond the member 23, to engage parts of the structure to hold the framework in place in the tank, for example as shown in Fig. 7, where the members 24 are extended upwardly adjacent the bars 25 extending across the top of the tank adjacent the edges of the icing cover 19. To facilitate convenient removal of the carrier supporting frames, the members 24 may be conveniently secured to the bars 25 by bolts and thumb nuts as indicated. The members 23 and 24 are preferably of metal and rigidly secured to each other at their crossing points, at which points they are bored to receive the ends of a shaft 26 extending through the carrier drums 20 to support them for turning movement. As indicated in Fig. 6, the ends of the shaft 26 are preferably shouldered as indicated at 26^a to positively retain the shaft in place in the supporting framework. Each of the carrier drums 20 is preferably constructed as indicated in Figs. 5 and 6 of sheet metal as follows: each drum consists of two sheet metal disks 27, having central apertures engaging the end portions of a sleeve 28, projecting sufficiently beyond the outer surfaces of the disks 27 to prevent the drum rubbing against the supporting framework and adjacent carrier drum, or against the adjacent drums as the case may be. Between the outer portions of the disks 27, radial partitions 29 are disposed, the size of the drum and the number of these partitions being so taken that the distance between two adjacent partitions circumferentially at the outer edge of the drum will be slightly greater than the outside diameter of the bottles to be handled by the drum, and further, so that the circumferential spacing between the partitions adjacent their inner ends will be but slightly greater than the outside diameter of the caps used to seal the bottles. Between the inner ends of each adjacent pair of partitions 29, I dispose circumferentially a bottom member 30 of sheet metal, for the corresponding bottle compartment in the drum, these bottom members 30 being separated enough to permit the inner ends of the partition members 29 to pass freely between them and be retained in place by them. The radial distance from the bottom members 30 to the outer edges of the disks 27 is so taken that the relation of each pair of partitions 29 to the adjacent bottle above described, is secured. To conveniently, quickly and effectively construct the drums, the partitions 29 are provided at their outer edges with pairs of lugs or ears 29^a, one pair for each disk, to extend through corresponding slots punched in the disks, one slot serving for each pair of ears. The

ends of the bottom members 30 are similarly provided with pairs of lugs or ears 30^a, to pass through corresponding slots in the disks 27, it being preferable that these slots in the disks 27 shall be arranged so that each will receive a lug of two adjacent bottom members 30, to simplify the punching of the slots in the disks. This permits the lugs 30^a to be on the extreme edges of the end portions of the bottom members, with a substantial separation between the lugs of each pair. Since the disks 27 are in parallel relation and necessarily separated a distance slightly greater than the outside diameter of the body portion of the bottles to be handled by the drum, I find it desirable to center the neck of the bottle in its compartment in the drum axially of the drum, and this I do by punching from the disks 27, tongues 31 and pressing them downwardly and inwardly towards the bottom members 30 as indicated in Fig. 6, a tongue being so formed from each disk between each adjacent pair of partitions 29. These tongues 31 are so formed and positioned after being inwardly bent against the bottom members 30, that the distance between the inner ends of each pair of tongues is slightly greater than the outside diameter of the bottle caps used to seal the bottles to be placed in the drums. As a result of this construction, when bottles are placed in the drums in the positions indicated at 14^a in Figs. 3 and 4, undue displacement of the bottles from radial positions, is prevented.

In making the drums, I find it desirable to first insert the lugs 30^a of the bottom members 30, through the two disks 27 of any drum and bend them securely against the disks. This permits the insertion of the partitions 29 one after another, by springing the disks 27 away from each other, and after all of the partitions have been inserted, with their inner ends between the bottom members 30 as described and their lugs 29^a extending through the disks, said lugs are bent over firmly against the outer surface of the disks 27 and thus the entire structure is positively secured together. The sleeve 28 may then be inserted and the entire structure further held together by soldering or by a tinning bath. It will be observed that the forming of the tongues 31 in the manner indicated leaves corresponding apertures 31^a in the disks 27 and that further apertures 31^b are also formed through the disks. The function of these apertures will be described later.

Each supporting framework constructed as above described, and consisting of the members 23 and 24, besides carrying a plurality of carrier drums constructed as above described, is provided with a plurality of guide rods 32 secured at their mid portions and end portions to the members 24 and 23 respectively of the framework. As indi-

cated in Fig. 4, each guide rod 32 is of generally semi-circular conformation and substantially concentric with the drum, one of these guide rods being secured to the supporting framework substantially in a plane through the mid portion of each drum. The radial distance between each guide rod 32 and the corresponding drum 20 is preferably such that there is a slight clearance 5 between the bottom of a bottle in place in the drum, and the guide rod so that as the drum is rotated with bottles in place therein, the bottles will slide on the guide rods in passing through the lower part of their 10 rotation with the drum. It is desirable that the ends of the guide rods be bent outwardly somewhat to slightly increase the clearance between the bottoms of the bottles and the guide rods, to insure easy and positive 15 entrance of the bottles into engagement with the guide rods. Since the guide rods are in frictional engagement with the bottles being moved by the drums upon them, it is desirable that the surface of engagement between the bottles and the rods be reduced 20 to a minimum and I therefore prefer to construct the guide rods of a cross section establishing line contact between them and the bottles, for example, a circular cross section. 25 It will be understood that the rods 32 may be of any material and cross section that will accomplish the result described. 30

I preferably secure to the adjacent portions of the supporting frameworks, perforated shielding plates 33 and 34 extending nearly to the tank 21, to define between them the space in which the ice may be confined, the perforations in the plates being too small to permit pieces of ice of appreciable size to pass through them. In using 35 the cooler, it is preferably about half filled with water, and therefore during the lower half of each rotation of any drum, the bottles carried by it are submerged in the water. The buoyant effect of the water on 40 the bottles materially reduces the friction that would otherwise occur between the bottles and the guide rods 32. The apertures 31^a and 31^b in the drums, permit free circulation of the water through the drums 45 and around the bottles carried thereby, effectively cooling the bottles. In spacing the bottom members 30 in each drum, it is preferable that slight clearances be left between the edges of the bottom members and 50 the adjacent partitions 29, so that when each drum is rotated to remove the bottles from the cooling water, the bottle compartments will drain and surplus water will be removed from the bottles before they are taken 55 from the cooler. 60

Each of the service doors permits ready access to the uppermost bottle in each of the two corresponding carrier drums, and a 65 cooled bottle may readily be removed by

opening the corresponding service door, and a warm bottle may then be inserted in the empty compartment in the carrier drum. The complete operation consists in opening the service door, removing the cooled bottle, inserting a warm bottle to be cooled, and then by means of the fingers pressing against the warm bottle to rotate the carrier drum to bring the next cooled bottle under the service door. The service door openings are made of but slightly greater size from front to rear, than the outside diameter of the bottles handled by the carrier drums and but small clearance is provided between the ends of the bottles and the inner surface of the main cover 11. This prevents moving any drum by one operation, a greater distance than that corresponding to unit spacing of the bottles in any drum and it is therefore practically necessary to move the drums step by step, one bottle at a time, due to the relation of dimensions referred to. Furthermore, in order to secure the next cooled bottle, it is necessary to rotate the drum in the manner described, and thus effective operation of each drum is insured without the use of operating or controlling mechanism of any kind. It will be observed that the operation of the drums is quite simple, and furthermore, that it is elastic in that it permits rotating the drums in either direction, or as much as desired before removing a bottle from any drum. This is sometimes desirable where a customer desires a bottle that has been somewhat chilled but not as cool as the completely cooled bottles would be. It will further be observed that there is a complete absence of springs and operating mechanism of any kind and that there is nothing to get out of order about the construction, the only wear the device is subject to being the wear of the drums on their supporting shafts and whatever wear may occur on the guide rods. 70 75 80 85 90 95 100 105 110 115

While I have shown my invention in the particular embodiment above described, it will be understood that I do not limit myself to this exact construction as I may employ equivalents known to the art at the time of the filing of this application without departing from the scope of the appended claims. 120

What I claim is:

1. In a bottle cooler, the combination of a tank for containing a refrigerant, a plurality of drums contained in said tank rotatable independently of each other, each drum comprising end disks and radial partitions forming compartments between the outer portions of said disks for receiving the necks and adjacent portions of bottles to be cooled, said disks having inwardly extending tongues at the bottom portions of said compartments cooperating with said parti- 125 130

5 tongues at the bottom portions of said compartments cooperating with said partitions to maintain bottles in said compartments in radial arrangement, a continuous rod in semi-circular form around the lower half of each drum forming a bearing support of small contact surface for the bottoms of bottles carried by said drum, a framework extending around said drums and secured to said semi-circular rods to support the same, 10 and a shaft extending centrally through said drums to support the same and supported by said framework, each of said drums also comprising a bottom wall for each of its bottle compartments and secured to the disks of said drum, said bottom walls being independent of each other and separated sufficiently to permit the inner ends of said partitions to extend between them to maintain the inner ends of said partitions in radial 20 lines, said partitions having side lugs at their outer ends and said bottom walls having end lugs extending through the disks of the corresponding drum and bent over against the outer surfaces of said disks.

25 7. In a bottle cooler, the combination of a tank for containing a refrigerant, a plurality of drums contained in said tank rotatable independently of each other, each drum comprising end disks and radial partitions forming compartments between the outer portions of said disks for receiving the necks and adjacent portions of bottles to be cooled, said disks having inwardly extending 30 tongues at the bottom portions of said compartments cooperating with said partitions to maintain bottles in said compartments in radial arrangement, a continuous rod in semi-circular form around the lower half of each drum forming a bearing support of small contact surface for the bottoms of bottles carried by said drum, a framework extending around said drums and secured to said semi-circular rods to support the same, 35 and a shaft extending centrally through said drums to support the same and supported by said framework each of said drums having a central bearing comprising a sleeve extending through said disks and secured thereto and projecting therefrom to effect clearance spaces between adjacent ones of said drums and between said drums and the ends of said framework, and said shaft being a free fit in said sleeves and having shouldered ends retaining it in 40 said framework.

45 8. In a bottle cooler, the combination of a tank for containing a refrigerant, a plurality of drums contained in said tank rotatable independently of each other, each drum comprising end disks and radial partitions forming compartments between the outer portions of said disks for receiving the necks 50 and adjacent portions of bottles to be cooled, said disks having inwardly extending tongues at the bottom portions of said compartments cooperating with said partitions to maintain bottles in said compartments in 55 radial arrangement, a continuous rod in

semi-circular form around the lower half of each drum forming a bearing support of small contact surface for the bottoms of bottles carried by said drum, a framework extending around said drums and secured to said semi-circular rods to support the same, 70 a shaft extending centrally through said drums to support the same and supported by said framework, said drums and said framework comprising a first assembled unit at one side of said tank, a second and similar assembled unit at the other side of said tank and separated from said first unit leaving an ice compartment in said tank, and a vertical perforated wall along each of said frameworks adjacent said ice compartment preventing engagement between ice in said tank and said drums and the bottles carried thereby.

75 9. In a bottle cooler, the combination of a tank for containing a refrigerant, a plurality of drums contained in said tank rotatable independently of each other, each drum comprising end disks and radial partitions forming compartments between the outer portions of said disks for receiving the necks and adjacent portions of bottles to be cooled, said disks having inwardly extending 80 tongues at the bottom portions of said compartments cooperating with said partitions to maintain bottles in said compartments in radial arrangement, a continuous rod in semi-circular form around the lower half of each drum forming a bearing support of small contact surface for the bottoms of bottles carried by said drum, a framework extending around said drums and secured to said semi-circular rods to support the same, 85 and a shaft extending centrally through said drums to support the same and supported by said framework each of said drums having a central bearing comprising a sleeve extending through said disks and secured thereto and projecting therefrom to effect clearance spaces between adjacent ones of said drums and between said drums and the ends of said framework, and said shaft being a free fit in said sleeves and having shouldered ends retaining it in 90 said framework.

95 10. A carrier drum for a bottle cooler, comprising the combination of end disks of sheet metal, radial partitions of sheet metal between and secured to said disks and separated angularly substantially the diameter of the neck and adjacent portions of bottles to be carried by said drum, and tongues of sheet metal extending obliquely between said partitions to engage the neck portions of said bottles axially of said drum to maintain 100 the axes of said bottles substantially in radial lines in the same plane.

11. A carrier drum for a bottle cooler, comprising the combination of end disks of sheet metal, radial partitions of sheet metal 105

- between and secured to said disks and separated angularly substantially the diameter of the neck and adjacent portions of bottles to be carried by said drum, tongues of sheet metal extending obliquely between said partitions to engage the neck portions of said bottles axially of said drum to maintain the axes of said bottles substantially in radial lines in the same plane, and bottom walls of sheet metal between said disks and secured thereto and separated sufficiently to permit the inner ends of said partitions to extend freely between them.
12. A carrier drum for a bottle cooler, comprising the combination of end disks of sheet metal, radial partitions of sheet metal between and secured to said disks and separated angularly substantially the diameter of the neck and adjacent portions of bottles to be carried by said drum, tongues of sheet metal extending obliquely between said partitions to engage the neck portions of said bottles axially of said drum to maintain the axes of said bottles substantially in radial lines in the same plane, and bottom walls of sheet metal between said disks and secured thereto and separated sufficiently to permit the inner ends of said partitions to extend freely between them, said partitions having edge lugs adjacent their outer ends extending through said disks and bent against the outer surfaces of the latter, the inner ends of said partitions being held in place by said bottom walls.
13. A carrier drum for a bottle cooler, comprising the combination of end disks of sheet metal, radial partitions of sheet metal between and secured to said disks and separated angularly substantially the diameter of the neck and adjacent portions of bottles to be carried by said drum, and tongues of sheet metal extending obliquely inwardly from said disks between said partitions to engage the neck portions of said bottles axially of said drum to maintain the axes of said bottles substantially in radial lines in the same plane, said tongues being cut from said disks and integral therewith and leaving circulation openings in said disks.
14. A carrier drum for a bottle cooler, comprising the combination of end disks of sheet metal, radial partitions of sheet metal between and secured to said disks and separated angularly substantially the diameter of the neck and adjacent portions of bottles to be carried by said drum, tongues of sheet metal extending obliquely between said partitions to engage the neck portions of said bottles axially of said drum to maintain the axes of said bottles substantially in radial lines in the same plane, and a sleeve extending centrally through said disks and secured thereto to form a bearing for said drum.
15. In a bottle cooler, a bottle carrier assembly comprising a skeleton framework, a

shaft carried by said framework, a drum rotary on said shaft, said drum having outwardly opening radial compartments to receive the neck portions of bottles, and a curved guide rod around substantially half of said drum to engage the bottoms of bottles in said compartments, said guide rod being secured to said framework and constituting a continuous guideway from end to end, said guide rod being of a cross section establishing single line contact with the bottles engaging it.

16. In a bottle cooler, a bottle carrier assembly comprising a skeleton framework, a shaft carried by said framework, a plurality of drums individually rotatable on said shaft, each of said drums having outwardly opening radial compartments to receive the neck portions of bottles, and a curved guide rod around substantially half of each drum to engage the bottoms of bottles in its compartments, each of said guide rods being secured to said framework and constituting a continuous guideway from end to end, each of said drums having a central sleeve comprising its bearing on said shaft and extending beyond the sides of its drum to maintain clearance spaces between said drums and between said framework and said drums.

17. In a bottle cooler, a bottle carrier assembly comprising a skeleton framework, a shaft carried by said framework, a plurality of drums individually rotatable on said shaft, each of said drums having outwardly opening radial compartments to receive the neck portions of bottles, and a curved guide rod around substantially half of each drum to engage the bottoms of bottles in its compartments, each of said guide rods being secured to said framework and constituting a continuous guideway from end to end, said shaft having shouldered ends engaging said framework to retain said shaft in place therein.

In witness whereof, I hereunto subscribe my name this 12th day of September, A. D. 1927.

JOHN M. SCHILLING.
